MOLDED PLASTIC PLATE

Clara Virginia Eicholtz, Midland, and Bertrand N. Trombley, Birmingham, Mich., assignors to Nyman Mfg. Co., Providence, R.I.

Filed Dec. 27, 1971, Ser. No. 212,843

Term of patent 14 years

Int. Cl. D7—01

U.S. Cl. D7—36

FIG. 1 is a top plan view of a molded plastic plate showing our new design;

FIG. 2 is a bottom plan view thereof;

FIG. 3 is a side elevational view thereof; and

FIG. 4 is an enlarged scale sectional view taken along line 4—4 of FIG. 1.

We claim:

The ornamental design for a molded plastic plate, substantially as shown.
